UNITED STATES PATENT OFFICE.

HOBART M. HINKEL, OF SPRINGFIELD, OHIO, ASSIGNOR OF ONE-FOURTH TO CARSON DINGES, OF SPRINGFIELD, OHIO.

WASHING MACHINE.

Application filed May 12, 1924, Serial No. 712,529.

To all whom it may concern:

Be it known that I, HOBART M. HINKEL, a citizen of the United States, residing at Springfield, in the county of Clark and State of Ohio, have invented certain new and useful Improvements in Washing Machines, of which the following is a specification.

This invention relates to improvements in washing machines of the rotating cylinder type.

One of the objects of my invention is to provide an unenclosed cylinder which is designed to contain both the clothes and washing fluid and which is arranged to be tilted from a horizontal to a vertical position or vice versa, whereby the cylinder may be placed in one position to receive the clothes and in another position when in operation.

A further object of the invention is to provide improved clamping means for securing the lid of the cylinder in position.

A further object of the invention is to devise a washing machine which will be simple in its construction, economical in manufacture and effective in use.

In the accompanying drawings:

Fig. 1 is a top plan view with the axis of rotation of the cylinder in horizontal position.

Fig. 2 is a side elevation of the same.

Fig. 3 is an end view of the cylinder.

Fig. 4 is a side elevation showing the cylinder tilted and its axis of rotation in vertical position.

Fig. 5 is a section on the line 5—5 of Fig. 3.

Fig. 6 is a detail sectional view showing the manner of supporting the cylinder.

Fig. 7 is a perspective view showing one of the sections containing the agitators on the interior of the cylinder.

Fig. 8 is a detail of one of the locking bolts and its keeper.

Referring to the drawings, 1 represents the longitudinal rails of the main frame, 2, 3 and 4 cross members, 5 legs and 5' braces connecting the legs. The cylinder is represented at 6; this cylinder having one end thereof closed by removable cover 7. The other end of the cylinder has connected therewith a spider 8, the hub 9 of which has secured thereto a horizontal longitudinally-extending shaft 10 provided with a clutch member 11. Journaled in bearings 13 on the

cross-members 2 and 3 is a shaft 14 aligned with the shaft 10 and having a clutch member 15 cooperating with the clutch member 11. The clutch member 15 is splined to the shaft 14 and slidably mounted thereon. An operating lever 16, having a pair of projections 17 to form a yoke which engages with an annular groove 18 in the clutch member 15, serves to shift the clutch member 15 into and out of engagement with the member 11. The shaft 14 is driven by an electric motor 19, the shaft 20 of which has a pulley 21 driving a pulley 22 on the end of the shaft 14 through the medium of a belt 23.

The cylinder 6 has secured thereto a circumferentially-extending ring 25 concentric to the axis of rotation, which ring fits in a grooveway formed by a channelled member 24 and is supported by the main frame in concentric relation with the ring; this member 25 having a pair of oppositely-arranged trunnions 26 journaled in bearings 27 supported by the frame bars 1. This ring 25 forms a support and track for the cylinder 6 while being revolved.

In order to place the clothes in the cylinder or remove the same therefrom the cylinder is tilted to the position shown in Fig. 4 in the following manner. Pivoted on the trunnions 26 is a yoke-shaped lever 28 the center of which is upturned as indicated at 28' and apertured so as to embrace the shaft 10. One end of the member 28 is extended, as indicated at 29, and the end of this extension is pivotally connected by a link 30 with an operating lever 31, pivoted at 32 to an ear 34 projecting from the main frame. To tilt the tub from the position shown in Figs. 1 and 2 to the position shown in Fig. 4 the lever 31 is thrown to the position shown in Fig. 4 which causes the link 30 acting on the extension 29 to swing the yoke 28 to the position shown and carry with it the cylinder. It should be stated that before the cylinder is tilted to this horizontal position the clutch members 11 and 15 are disconnected. At the point where the link is pivoted to the lever 31 the lever 31 is offset, as indicated at 31', so that when it is thrown to the position shown in Fig. 4 the pivotal point between the lever and link will swing past a line extending between the pivotal point of the lever and link and the pivotal point of the

link and extension 29 and thus lock the parts.

The interior of the cylinder is provided with a series of sections 35, one of which is shown in Fig. 7, and each of these sections has a series of ribs 36, to form carriers and agitators, the center one of which is enlarged as shown so as to act to prevent the clothes from banking in the cylinder.

10 To clamp the lid 7 to the rim 6' of the cylinder I provide the lid with a rotatable spindle 37 provided with a handle 38' and having thereon a disk 38 to which are pivoted a series of links 39, each link being pivotally attached to a bolt 40. The bolts extend radially and engage with a series of keepers 41 on the rim 6'. The outer end of each bolt is formed with a bevelled nose 42, as indicated in Fig. 8, and the inner end of 15 the bolt is provided with a T-shaped head 43 which projects through a slot 44 in the outer wall of the lid; the lid being formed of two spaced-apart panels 7 and 7' as shown in Fig. 5. As a result of this arrangement, 20 when the spindle 37 is rotated the bolts 40 will be projected outwardly to cause their pivotal noses to engage the keepers and thus cause the lid to be clamped firmly against the ledge or flange 6'' (shown in dotted lines 25 in Fig. 3) projecting from the inner edge of the rim 6'.

Having thus described my invention, I claim:

1. In a washing machine, an unenclosed cylinder adapted to receive the clothes and washing fluid, a pivoted annular member upon which said cylinder is mounted to rotate, means for rotating said cylinder, said means being arranged in line with the axis 35 of rotation of said cylinder and including a clutch, a removable lid for one end of said cylinder, and means for tilting said cylinder together with its supporting member to

bring the lid in an upper horizontal position.

2. In a washing machine, an unenclosed cylinder adapted to contain clothes and washing fluid, a removable lid for one end of said cylinder, means for rotating said cylinder on a horizontal axis, a ring secured to 50 said cylinder concentric to the axis of rotation, a pivotally mounted supporting channelled member concentric with said ring in which said ring is revolvably mounted, and means for tilting said cylinder and supporting member to bring the axis of rotation in a vertical position with the lid in an 55 upper horizontal position.

3. In a washing machine, an unenclosed cylinder adapted to receive the clothes and washing fluid, a horizontal shaft connected with said cylinder, a horizontal drive shaft in alignment with said cylinder shaft, clutch members between said shafts together with means for connecting and disconnecting the 60 same, a pivotally mounted channelled member concentric with the axis of rotation of said shafts for rotatably supporting said cylinder, and a lever connected with said cylinder shaft for tilting said cylinder about 65 the pivotal points of said channel member for the purpose specified.

4. In a washing machine, an unenclosed cylinder adapted to receive the clothes and washing fluid, a pivoted support in which 70 said cylinder is rotatably mounted, a shaft connected with said cylinder, means for driving said shaft, a pivotally mounted yoke-shaped lever connected with said shaft having an extended arm, a pivotally mounted operating lever, and a link connecting said operating lever with said extended arm.

In testimony whereof, I have hereunto set my hand this 10th day of May 1924.

HOBART M. HINKEL.
